United States Patent Office.

THEODORE R. TIMBY, OF TARRYTOWN, NEW YORK.

Design No. 4,499, dated November 29, 1870.

DESIGN FOR A MEDAL.

The Schedule referred to in these Letters Patent and making part of the same.

I, THEODORE R. TIMBY, of Tarrytown, in the county of Westchester and State of New York, have invented a new Design for Medals, of which the following is a specification.

Nature and Objects of the Invention.

The nature of my design for medals is correctly represented in the accompanying drawing of the respective sides of the model.

Figure 1 shows the obverse, on which an ornamental design is represented.

Figure 2 shows the reverse, containing mottoes, which admit of variation.

My object is to provide a medal with an inscribed pledge on the same, also a medal with a forfeit inscribed thereon, for the use of schools of any character, whether Sabbath, select, common, grammar, or district schools.

I claim—

The design for medals, substantially as above set forth.

THEODORE R. TIMBY.
